UNITED STATES PATENT OFFICE.

RICHARD WILLIAM DERBYSHIRE, OF DAGENHAM, ENGLAND.

TIDAL MOTOR.

SPECIFICATION forming part of Letters Patent No. 700,408, dated May 20, 1902.

Application filed March 10, 1902. Serial No. 97,466. (No model.)

To all whom it may concern:

Be it known that I, RICHARD WILLIAM DERBYSHIRE, engineer, a subject of the King of Great Britain and Ireland, and a resident of the 5 Cross Keys, Dagenham, in the county of Essex, England, have invented certain new and useful Improvements in Tidal Motors for Use in Generating Electricity, (for which I have applied for a patent in Great Britain, No. 10 4,305, bearing date February 28, 1901, which has been filed but not yet sealed,) of which the following is a specification.

My invention relates to the utilization of a tidal rise or fall and the current of water-flow 15 incidental thereto for operating a dynamo-electric generator and using the energy derived therefrom for driving motors, working electrical lamps, and for like purposes.

In order that my invention may be clearly 20 understood, I have appended the accompanying sheet of drawings, in which—

Figure 1 is a sectional elevation of the general device. Fig. 2 is an end elevation thereof, also sectional. Fig. 3 is an elevation of 25 part of the outer ring, showing the means adopted for varying the angle of the buckets. Fig. 4 is an end sectional elevation thereof; and Fig. 5 is a view of the outer ring, showing the screwed lug in place within the slot.

Similar letters of reference indicate corresponding parts throughout the several views.

In carrying my invention into effect I employ a moored raft or barge with either "swim-headed" or tapered ends, which is placed in 35 a tideway and has a central channel B, suitably shaped to provide for the rotation of the undershot C by the water-current set up by the tide. The buckets b may be set to any angle within their range by a slotted ring D 40 on one side and a guide-ring D' on the other side, these rings being joined by cross-bars E, passing from D to D' under the periphery F of the wheel C and between the arms thereof, so that both rings may move simultaneously. The cross-bars E slidably bear on the 45 annular flange F' on the inner side of the periphery F of wheel C, and so maintain the rings D D' in a concentric position on the wheel C. Each bucket b is freely bedded 50 in the periphery F, between a pair of angle-strips F' on said periphery, and attached by free pivots or pins c to the rings D D',

which form the sides of the wheel. A head H, similar to the puppet-head of a lathe, is attached to D and has a screw J, which 55 engages with a screwed hole in the lug K, which is attached to and projects from the periphery F, upon which the buckets b are freely swung. A hand-wheel I controls the screw J, and when it is desired to reverse the 60 angle of the buckets b or to regulate said angle the hand-wheel I is turned in either direction, so as to move the slotted ring D and the opposite ring D' relatively to the periphery F. Said regulation or reversal is effected 65 by stopping the wheel C by a sluice gate or gates temporarily during adjustment. Since the apparatus is carried upon a floating raft or split barge, the immersion is always equal. I prefer to couple the wheel C thus driven directly to one or more dynamo-electric generators M M' and either ballast the barge or raft with accumulators in circuit or use the 70 current derived directly.

I may use two, three, or more wheels C in 75 the parallel space between the flotation portions of the raft, barge, or the like and may grade them so that each may take up the backwater of the preceding one and the power be delivered upon a spindle or shaft 80 common to all.

Having now particularly described and ascertained the nature of my said invention and in what manner the same is to be performed, I declare that what I claim is—

1. In a device of the character described, a wheel, rings carried by the wheel and adjustable thereon, and buckets mounted in the 85 wheel and rings.

2. In a device of the character described, a wheel, a ring carried by the wheel and adjustable thereon, and buckets pivoted in the ring and loosely seated on the wheel.

3. In a device of the character described, a wheel, rings adjustable thereon, buckets pivoted in the rings and angle-strips on the periphery of the wheel between which the ends of the buckets are loosely held.

4. In a device of the character described, a wheel having a flat periphery with an annular flange on its inner side, a ring on each side of the periphery, cross-bars connecting the rings and slidably bearing on the flange, buckets pivoted to the rings and loosely

seated on the periphery of the wheel, and means for adjusting the rings on the wheel.

5. In a tidal motor, a raft or divided barge, an undershot wheel mounted thereon, buckets carried by the wheel and means for simultaneously altering the incline of all of the buckets of the wheel.

In witness whereof I have hereunto set my hand in presence of two witnesses.

RICHARD WILLIAM DERBYSHIRE.
